UNITED STATES PATENT OFFICE.

HERMANN ESSER, OF HOBOKEN, NEW JERSEY.

DESIGN FOR A FORK FOR DIVIDERS.

SPECIFICATION forming part of Design No. 22,295, dated March 14, 1893.

Application filed December 14, 1892. Serial No. 455,198. Term of patent 14 years.

To all whom it may concern:

Be it known that I, HERMANN ESSER, a citizen of the United States, residing at Hoboken, in the county of Hudson and State of New Jersey, have invented and produced a new and original Design for Forks of Dividers, of which the following is a specification, reference being had to the accompanying drawings, showing a part thereof.

Figure 1 is a side elevation, and Fig. 2 an edge view.

The leading feature of my design consists in a fork having a circular enlargement at the end of each of the arms.

A is the body of the fork, and A', A', the

circular enlargement on the lower end of each branch or arm thereof. The outer face of each circular enlargement A' on the ends of the fork A is grooved around near its periphery, as indicated by a.

20

What I claim is—

The design for forks of dividers, herein shown and described.

In testimony that I claim the invention above set forth I affix my signature in presence of two witnesses.
